ROBERT D. MOORE AND ONE-THIRD TO ROBERT R. ROBERTS, BOTH OF FAIRFAX,
WASHINGTON.

AUTOMATIC ELECTRIC-LAMP LOCK.

1,192,749.

Specification of Letters Patent. Patented July 25, 1916.

Application filed December 8, 1915. Serial No. 65,744.

To all whom it may concern:

Be it known that I, DELONA L. CALAHAN, a citizen of the United States, residing at Fairfax, in the county of Pierce and State 5 of Washington, have invented a new and useful Automatic Electric-Lamp Lock, of which the following is a specification.

The present invention is a device for locking an incandescent lamp to its socket, to 10 prevent the theft or removal of the lamp or bulb without breaking or destroying the same so as to render the lamp useless.

It is the object of the invention to provide a novel yet simple and effective means 15 in a lamp socket for locking the plug of the lamp within the socket member to prevent the loss of the lamp, the locking means being normally concealed so as not to be accessible and being readily exposed when the 20 bulb is broken, in order that the plug of a burnt out lamp can be removed for the substitution of a new lamp.

The loss of electric lamps by theft in factories, mills, public buildings and the like, 25 amounts to a considerable item, but with the use of sockets embodying the present improvements, this loss will be eradicated, since the lamps cannot be removed without breaking the bulbs thereof, and which would naturally 30 prevent the thefts of the lamps, the lamps being readily replaced when they are burnt out.

The invention resides in the provision of a spring catch or pawl applied to the socket 35 member of the lamp socket for holding the plug of the lamp therein, the provision of an opening in the shell of the socket for exposing the catch so that it can be manually released, and the provision of a cuff or collar 40 normally concealing said opening and held in place by the bulb of the lamp, so that said cuff cannot be removed until the bulb is broken. Thus, when the plug of the lamp is threaded into the socket member, the catch 45 engages the plug to prevent the unscrewing thereof, and the bulb of the lamp will retain the cuff in position, whereby said cuff cannot be withdrawn from the shell of the socket until the bulb is broken. This can 50 readily be done when the lamp is burnt out, and the cuff in being removed will permit an implement to be inserted through the opening of the shell, for releasing the catch, so that the holder plug can be unscrewed.

and removed for the substitution of a new 55 lamp.

It is also within the scope of the invention to provide a locking device of the nature indicated which can be provided in a simple and convenient manner upon ordinary lamp 60 sockets, as well as new ones, without requiring any changes in the construction of the lamp socket itself or entailing prohibitive trouble or expense.

With the foregoing and other objects in 65 view which will appear as the description proceeds, the invention resides in the combination and arrangement of parts and in the details of construction hereinafter described and claimed, it being understood that 70 changes in the precise embodiment of the invention herein disclosed can be made within the scope of what is claimed without departing from the spirit of the invention.

The invention is illustrated in the accompanying drawing, wherein:—

Figure 1 is a side elevation of a lamp socket and lamp in locked position, the cuff being shown in section. Fig. 2 is a cross section on the line 2—2 of Fig. 1. Fig. 3 is 80 a fragmental elevation of the lamp showing the plug provided with an aperture for the engagement of a catch. Fig. 4 is a plan view of the catch. Fig. 5 is a plan view of an implement which is preferably used in 85 connection with the lock.

In the drawing, there is illustrated an ordinary lamp socket embodying a metallic shell 1 inclosing the threaded socket member 2 as usual.

In carrying out the invention a spring catch 3 is applied to the socket member 2, said catch being in the form of a leaf spring extending through an arc of over 180°, and provided at one end with a hook-shaped spur 95 or pawl 4. The catch 3 is snapped onto the socket member 2 so as to embrace the same and lie within the groove of the thread of the said socket member at the proper point, and an aperture 5 is punched in the socket 100 member 2 so that the spur 4 projects inwardly through said aperture.

The shell 1 of the socket is provided with an opening 6 adjacent the socket member 2 and exposing that end of the catch 3 having the spur 4, in order that said spur can be retracted manually when the opening 6 is uncovered.

The spur 4 is engageable in an aperture 7 punched in the shell of the plug 8 of the lamp or bulb 9, whereby when the plug 8 is screwed into the socket member 1, the spur 4 will spring into the aperture 7 when the lamp is screwed home, to thereby prevent the unscrewing of the lamp from the socket.

In order to normally cover the opening 6 to prevent access being had to the catch of the lock, a cuff or collar 10 is slipped onto the shell 1 around the socket end thereof to cover the opening 6, and the outer end of the cuff 10 is contracted, as at 11, to bear against the bulb of the lamp, whereby said bulb holds the cuff 10 in place upon the shell.

The implement illustrated in Fig. 5 is preferably used in connection with the lock, and embodies a shank 12 attached to a suitable handle 13 and having a flattened head 14 provided with an open slot 15 and a point 16.

The socket can be readily provided with the improved features, since the catch 3 can be readily placed upon the socket member 2 before the shell 1 is applied, the aperture 5 being readily punched in the socket member 2 by means of the point 16 of the implement.

The aperture 7 is also punched in the plug 8 by means of the point 16 of the implement, and the cuff 10 is then placed upon the shell 1. Then, when the plug of the lamp is threaded into the socket member 2, it will force the spur 4 outwardly until the aperture 7 reaches said spur, in which event the spur 4 will spring into the aperture 7. The locking means is in the form of a ratchet device to permit the plug to be screwed into the socket member, but to prevent the plug from being unscrewed, it being noted that the spur 4 is of hook-shape so that it will effectively prevent the unscrewing of the plug. The spur 4 in projecting through the aperture 5 will hold the catch 3 in place relative to the socket member, and the bulb of the lamp will hold the cuff 10 upon the shell 1, and prevents access being had to the catch 3. It is thus impossible for a maliciously inclined person to remove the lamp for purpose of theft or otherwise, unless the bulb of the lamp is broken.

To renew the lamp when it is burnt out, the bulb is broken, thereby releasing the cuff 10 so that said cuff can be withdrawn from the shell 1. This enables the point 16 of the implement to be inserted through the

opening 6 for prying up the end of the catch 3, to retract the spur 4 from the plug 8. If desired, the spur 4 can be moved to one side to rest against the periphery of the socket member 2, and the implement can then be used as a wrench for unscrewing the plug, the slot 15 being engaged with the flattened terminal 17 of the filament supporting tube 18 which projects from the plug, said tube being exposed due to the breaking of the bulb. The implement may thus be used as a wrench for unscrewing the plug conveniently and without danger. After the plug is removed, the catch is replaced, as well as the cuff 10, and a new lamp can be screwed into the socket as before, the aperture 7 being provided in the plug of the lamp before it is screwed in place.

Having thus described the invention, what is claimed as new is:

1. In a lamp socket, a shell, a socket member therein having a plug engaging catch, said shell having an opening exposing said catch, whereby the catch can be released, and means held in place by the bulb of a lamp for covering said opening and concealing said catch.

2. In a lamp socket, a shell, a socket member therein having a catch for engaging the plug of a lamp to prevent the unscrewing thereof, said shell having an opening exposing said catch whereby it can be released, and a cuff upon the shell covering said opening to conceal the catch and held in place by the bulb of the lamp.

3. In a lamp socket, a shell, a threaded socket member therein having an aperture, a spring catch extending through an arc of over 180° and embracing said member and lying within the groove thereof, the socket member having an aperture and one end of said catch having an inwardly projecting spur projecting through said aperture to engage a lamp plug for preventing the unscrewing thereof, said shell having an opening exposing that end of the catch having said spur, and a cuff adapted to be slipped upon the shell to cover said opening and to be held in place by the bulb of the lamp.

In testimony that I claim the foregoing as my own, I have hereto affixed my signature in the presence of two witnesses.

DELONA L. CALAHAN.
